UNITED STATES PATENT OFFICE

172,501

DRIER

Elmer S. Hewitt, Wilmette, and Louis E. Beyer,
Bellwood, Ill., assignors to Electric-Aire En-
gineering Corporation, a corporation of Illinois

Application December 29, 1953, Serial No. 28,265

Term of patent 14 years

(Cl. D4—3)

To all whom it may concern:

Be it known that we, Elmer S. Hewitt and Louis E. Beyer, citizens of the United States, residing at Wilmette, county of Cook, and State of Illinois, and Bellwood, county of Cook, and State of Illinois, respectively, have invented a new, original, and ornamental Design for a Drier, of which the following is a specification, reference being had to the accompanying drawings, forming a part thereof, in which:

Figure 1 is a front elevational view of a drier, showing our new design.

Figure 2 is a top plan view of said drier.

Figure 3 is a side elevational view of said drier.
Figure 4 is a bottom plan view of said drier.

We claim:

The ornamental design for a drier, as shown.
